UNITED STATES PATENT OFFICE

WILLIAM H. ACHURCH, OF PROVIDENCE, RHODE ISLAND, ASSIGNOR TO GORHAM
MANUFACTURING COMPANY, OF PROVIDENCE, RHODE ISLAND

DESIGN FOR A CHALICE

Application filed July 16, 1932. Serial No. 44,356. Term of patent 14 years.

To all whom it may concern:

Be it known that I, WILLIAM H. ACHURCH, of Providence, in the county of Providence and State of Rhode Island, have invented a new, original, and ornamental Design for a Chalice, of which the following is a specification, reference being had to the accompanying drawing, forming part thereof.

I claim:

The ornamental design for a chalice, as shown.

In testimony whereof I have signed my name to this specification.

WILLIAM H. ACHURCH.
